MORTUARY SUPPORT

Emerson G. Behrens, Leslie, Mich.

Application November 6, 1947, Serial No. 784,388

4 Claims. (Cl. 27—21)

1

This invention relates to mortuary or embalming tables, and more particularly to equipment used by morticians in connection with the use of their embalming tables.

With few exceptions, most morticians embalm a dead human body by placing that body directly on their embalming table and working on the body as it rests on the embalming table. The embalming operation consists in various draining, injecting, and packing operations, and is completed with the dressing of the body for burial and its removal to a slumber couch before it is placed in a casket. These draining, injecting and packing operations are necessarily somewhat messy and certainly odorous. To cope with the messiness and the odorous part of the operation, the embalming table is designed with a convex surface having guttered edges so that the drainage may be washed from around the body into the guttered edges and out a drain. This draining operation is normally accomplished by the use of a hose through which water is run practically all of the time, the water being directed around on various places as it is needed.

Another problem which is often met by morticians is that connected with the body which refuses to maintain a position in which it may be readily embalmed. Such bodies are those of extremely corpulent people, those bodies having extremely round shoulders or a projecting spine, and extremely emaciated bodies. All of these types tend to slide or roll around on the convex table top to such an extent that working on them is very difficult. It is likewise true of all bodies that, when they are laid on the convex top embalming table, the feet tend to turn out at the toes and to slide around on the table which is normally wet and therefore slippery. Various makeshift arrangements are used to prevent the sliding around of these particular types of bodies and the movement of the feet of all bodies, these arrangements contributing to cluttering up the table top while they are in use, since they consist of tying the feet together with rags or rope, propping the arms up out of the table gutter by means of bottles or pieces of metal, and in various ways attempting to hold the body in a single position so that it may be embalmed.

A still further problem presents itself when the mortician attempts to dress the body for burial, in that it is usually necessary to wash the body after the embalming operation, and the wet body then remains on the wet and not always clean embalming table until it is dressed. When attempting to dress a wet body, the embalmer often finds that he has soiled the clothing being used,

2

oftentimes to such an extent that it must be changed, and always to the extent that it must be at least washed off so that the stains and the accompanying odors will not be apparent to those who later view the body. A further problem which arises in connection with the dressing operation comes from the fact that, in order to dress the body without slitting the clothing being used, it is necessary to move the body somewhat in order to get the clothes under the back of the corpse. This movement of the body oftentimes disturbs the facial arrangement and necessitates repeating part of the work already finished. This is not only time consuming but uneconomical, and often the repeated job is not as satisfactory as the first one.

It is therefore an object of this invention to provide a support to be used on an embalmer's table to hold dead human bodies in a position up 10 off the table and free from drainage residues.

Another object is to provide a mortuary support which is completely adjustable to hold the body of a small child or the body of a large adult.

It is also an object to provide a support which 20 will hold a body in position for embalming so that the body will not slip, roll or slide from the selected position.

A further object is to provide a support which 25 will hold a body up over a table so that the table may be kept clean, sanitary and free from stains and odors.

Another object is to provide a support which 30 incorporates a water supplying apparatus giving a constant flow of water at the proper places on the embalming table to remove all traces of drainage therefrom.

A further object is to provide a completely 35 self-contained support which holds the bodies in the best embalming position and eliminates former table top clutter and makeshift arrangements used to hold the bodies in such a position.

A further object is to provide a support for 40 bodies which holds a dead body in the desired position while rigor mortis sets in, thereby obtaining a better posture arrangement of the body.

A further object is to provide a support which 45 will hold a body so that it can be completely washed before dressing without disturbing it in any way.

A further object is to provide a support which 50 will hold the body in the desired position and yet which is almost completely covered by the body so that the support itself does not become stained or unsanitary.

A still further object is to provide a support

which will hold the body in position after it is washed so that it may be dried and the table dried in order that clothing will not be soiled in the dressing operation.

A still further object is to provide a support which will hold the body so that it may be dressed normally from the head and the feet.

A still further object is to provide a support which will allow the operator to dress the body without splitting any clothing.

A still further object is to provide a support which will allow the dressing of a dead human body without rolling, moving or disturbing the body or the arrangement of the face.

Still further objects and advantages inherent in the construction of my invention will be apparent from a consideration of the following specification in connection with the appended claims and accompanying drawings in which,

Fig. I is a plan view of my mortuary support,

Fig. II is a view in elevation of the right side of my mortuary support,

Fig. III is a view similar to Fig. II, but with the mortuary support in position for dressing the body, and a body indicated in dotted outline,

Fig. IV is a view in partial section on the line IV—IV of Fig. I,

Fig. V is a view in partial section on the line V—V of Fig. I,

Fig. VI is a view on the line VI—VI of Fig. I, and

Fig. VII is a broken plan view of the pelvis shield.

As shown in the drawings, my invention comprises essentially a lower supporting structure, an attached upper supporting structure, and an associated water conducting and distributing apparatus.

The lower supporting structure comprises a frame composed of a longitudinal member 12 which is bent as at 14 to form a leg 16 over which is installed a rubber foot 18. The longitudinal member 12 is attached to the sleeve 20 by inserting its one end inside the aperture 22 and holding it in position by a pin or set-screw 24. The underside of the longitudinal member 12 is channeled as at 26 for reasons which will appear later.

The end of the sleeve 20 opposite the aperture 22 is Y-shaped, and presents the apertures 28 and 30 which receive the ends 32 and 34 of the side frames 36 and 38 which are bent toward each other at 40 and 42 and enter the apertures 44 and 46 in the saddle 48 which completes the triangle. As will be seen from Fig. I and Fig. VI, the side supports 36 and 38 are fitted fairly loosely into the apertures 44 and 46 in the saddle 48 so that the saddle 48 is free to rotate for a few degrees about the axis of the apertures 44 and 46. The side leg members 50 and 52 are attached to the fittings 54 which embrace the side support members 36 and 38, and are also fitted with rubber feet 56. The structure thus far described comprises essentially a triangular frame supported on two legs, and attached to an extended longitudinal supporting member, which is in turn supported on a third leg, which three-point support will allow this portion of my invention to be placed on any convex mortuary table and to be used without tipping or rocking because of improper support.

The body supporting portions of the lower frame 10 comprise the foot stirrups 58 and the buttocks pan 60. The foot stirrups 58 are mounted on a horizontal bar 62 to which is attached a collar 64 having a knurled screw 66 which passes through its lower side and engages the channel

26 in the longitudinal member 12. The bar 62 supports the individual stirrup portions 68 and the particular mounting with the screw 66 engaging the channel 26 prevents rotary movement of the stirrups 58 about the axis of the longitudinal member 12. It is also apparent, that the stirrup 58 is completely adjustable longitudinally relative to the member 12, since it may be positioned adjacent the sleeve 20 or almost adjacent the leg 16.

The buttocks pan 60 is shaped to cover completely the triangular frame comprising the side supports 36 and 38 and the saddle 48, and is built wide enough to support a large body even though it extends outside the frame structure. The buttocks pan 60 is likewise formed with a triangular opening 70 and a rectangular opening 72, the purposes of which will appear later. The pan 60 is attached to the frame structure by the suspended lips 74 which embrace the side members 36 and 38, and the resilient metal clips 76 which grip the members 36 and 38 adjacent the saddle 48. In installing the buttocks pan 60 on the frame 10, it is necessary to slide the pan 60 up over the frame members 36 and 38 so that the suspended lips 74 will engage the members 36 and 38, and then the clips 76 are forced down over the members 36 and 38. The structure thus far described will support the hips, legs and feet of a dead human body in position for embalming.

The water conducting apparatus of my invention is associated with the lower frame 10, and comprises a pipe 78 which is mounted parallel to the member 12 and attached thereto by means such as clips 80, and having its free end 82 adjacent the foot leg 16 so that a water hose 84 may be attached thereto to conduct water from a convenient source into the system. The end of the pipe 78 opposite the end 82 projects through the buttocks pan 60 at 86 and enters the union 88. The pipe 90 is joined to the union 88 and runs parallel to the member 36 to a point adjacent the leg 50 where it turns and runs across underneath the upper end of the buttocks pan 60 to a point adjacent the leg 52. The spray fittings 92 are attached to the pipe 90 adjacent the legs 50 and 52, and are formed to emit a continuous web of water, somewhat fan-shaped, over the area under the buttocks pan 60. The T-fitting 94 is mounted in the pipe 90 adjacent the leg 50, and carries water into the hose 96 which is attached thereto and adapted to conduct water up underneath the head portion of the entire support, as needed. I have therefore provided a water distribution system which accepts water from a source 84, conducts it through a pipe 78 into a pipe 90, sprays the water into the most needed positions through the fittings 92, and conducts it up around the head portions of the entire support through the rubber hose 96.

The supporting structure of the upper end of my mortuary support is composed essentially of a U-shaped member which, because of its shape, I have termed the hairpin 98, which is removably received through the apertures 100 and 102 in the upper supporting block 104 as well as the apertures 106 and 108 in the saddle 48. The upper supporting block 104 stands on a leg 110 which is normally situated in the drainage gutter 112 of the table 114. A set screw 116 is provided on one side of the upper supporting block 104 to position the hairpin 98 relative to the block 104. By supporting the hairpin 98 through the block 104, which is held in position by reason of its 75 foot 110 being engaged in the gutter 112, and

by passing the other end of the hairpin 98 through the apertures in the saddle 48, I have obtained a three-point suspension for the hairpin 98 and the upper supporting structure, by reason of the hinged supporting action of the saddle 48, so that the upper supporting structure is supported on the legs 110, 50 and 52.

The head cup 118, formed approximately to the shape of the average head, is pivotally mounted on the shaft 120, and is held in position relative thereto by the set-screw 122. The stub shaft 120 is supported by the bifurcated leg 124 which is in turn pivotally mounted on a stub shaft 126 in the supporting block 128. The inclination of the supporting leg 124 is controlled relative to the block 128 by the arcuate ratchet member 130 which is pivotally mounted on the stub shaft 132, between the legs 124, and engages the pawl 134 in the block 128, being urged into its operative position by the spring 136. The block 128 is formed with a pair of apertures 138 and 140 through which the hairpin 98 extends, and is fitted with a set-screw 142 which will hold the block 128 against movement relative to the hairpin 98. From this it will be seen that I have provided a head cup 118 which is adjustable longitudinally relative to the hairpin 98, which is adjustable vertically relative to the hairpin 98 and the embalming table, and whose inclination is adjustable relative to the plane of the embalming table so that the particular neck angle and head position desired may be obtained easily.

The supporting block 144 for the shoulder pan 146 is slidably mounted on the hairpin 98 through the apertures 148 and 150, and supports the figure-8-shaped shoulder pan 146 directly. The extremities of the supporting block 144, outside the hairpin 98, are formed to support the fittings 152 which are held in place by the pins 154. The portions 152 are telescopically received within the extendible arms 156 whose complete removal therefrom is prevented by the stud 158 which is attached thereto and which rides through the channel 160. The arms 156 support at their outer extremities the elbow cups 158 whose stems 160 are removably received through the apertures 162 and held in the desired position by the set-screws 164. It will be readily understood that the elbow cups 158 are adjustable vertically away from the embalming table and in a horizontal plane by reason of their pivoted connection at the pin 154 with the supporting block 144.

To aid in compliance with ethical considerations and to preserve the modesty of the dead from chance visitors to the embalming room, I have provided, as shown in Fig. VII, a pelvis shield 166 to be used to cover the pelvic region of the dead body during most of the embalming. The shield 166 is fashioned preferably of a rubber impregnated or similar material, and is provided with grommets 168 at each of its three corners to receive the varied length hooks 170 engageable in the apertures 172 in the buttocks pan 60, and to receive the S-hook 174 engageable with the ring 176 which encircles the lower part of the support 10, preferably around the member 20. The positioning of the ring 176 and the triangular shape of the shield 166 will make it extremely easy to preserve the modesty of the dead, while the use of varied length hooks 170, or the substitution of rubber-cord for these hooks, will make it possible to use the shield for bodies of varying sizes.

In operation, my support is assembled as shown in Figs. I and II and placed upon a mortuary

table with the leg 110 engaged in the gutter 112 at the head end of the table. The hose 84 is attached to the end 82 of the pipe 78, and, if it has been previously removed, the hose 96 is attached to the T-fitting 94. The body is next placed on the mortuary support in a position in which the hips are supported by the buttocks pan 60 in such a way that there is no tendency for the hips to roll from the support or to slip in any fashion. In the case of very emaciated bodies, it will be found advisable to slightly wedge the hips into the aperture 70 within the buttocks pan 60 in order to prevent any such rolling. After the body is positioned as above, the shoulder support 146 is positioned beneath the shoulders of the body, and the head cup 118 is adjusted to support the head in the desired position and at a proper angle. The arms may now be positioned as desired, and supported by the elbow cups 158. The final operation is the positioning of the foot stirrups 58 and the tightening of the set-screw 66 to hold the feet in the desired position. The water may now be turned on and the embalming operation performed, after which the body may be washed and dried so that it is ready to receive the clothing. Prior to dressing the body, the set-screws 116 and 142 are released from engagement with the hairpin 98, and the hairpin 98 is pulled longitudinally through the apertures 100 and 102, and 138 and 140, away from the saddle 48, so that the open end of the hairpin 98 drops to the table as shown in Fig. III. Rigidity having set in by this time, due to the embalming process, the body is supported from the buttocks pan 60 and the head cup 118, in which position it will be found possible to dress the body in the normal manner, without splitting any clothing, and without soiling the clothing. The dressing operation will likewise not require the moving of the upper extremities of the body or disturbing of any facial arrangement, moving, lifting or falling of the head. Following the completion of the dressing operation the body may be removed to a slumber couch and the apparatus readied for another embalming.

Having thus described my invention, what I claim as new and desire to protect by Letters Patent is:

1. A support for a human body comprising a first frame member, leg and buttocks supporting portions positioned on said first frame member, a second frame member, head and shoulders supporting portions positioned on said second frame member, means for supporting said head portion for longitudinal adjustment along said second frame member, a plurality of legs attached to said frame members to support said frame members above a mortuary table, longitudinally telescoping attachment parts upon said frame members to connect said frame members together in one of their operating positions, said parts being disengaged upon relative longitudinal movement between said frame members to place said frame members in another of their operative positions without removing the human body therefrom.

2. A body supporting structure comprising a first frame member, a second U-shaped frame member, legs associated with said frame members to support said frame members above an embalming table, an open center buttocks pan attached to said first frame member adjacent one end thereof, attachment structure associated with said first frame member in juxtaposition to said buttocks pan, said attachment structure having a pair of apertures therein and adapted

to slidably receive said second frame member to permit said second frame member to extend across said open centered buttocks pan to support small or thin bodies which might slip through said open centered buttocks pan.

3. A body supporting device for use on an embalming table comprising a frame, leg structure adapted to hold said frame above said embalming table, body supporting portions associated with said frame and comprising a shoulder supporting portion slidably mounted on said frame for adjustably positioning said shoulder supporting portion relative to the other body supporting portions, a pair of extendible arms pivotally mounted on said shoulder supporting portion adjacent said frame for radial movement in a plane substantially parallel to said embalming table, and an elbow cup slidably mounted adjacent the end of each of said extendible arms for vertical movement in a plane substantially perpendicular to the plane of movement of said arms to support the arms of a corpse in any one of a number of positions, as desired.

4. A mortuary support comprising a plurality of body supporting portions, a leg supported frame

5 member adapted to support at least one of said body supporting portions, a second frame member at least partially supported by said first frame member and adapted to support at least one of said body supporting portions, said second frame member being U-shaped, and a saddle mounted on said first frame member for rotary movement with respect thereto and having a pair of apertures adapted to receive the legs of said U-shaped

10 second frame member for guided relative longitudinal movement with respect to said first frame member.
